(57) **CLAIM**

The ornamental design for fishing pliers, as shown and described.

DESCRIPTION

FIG. 1 is a perspective view of the fishing pliers according to the present invention;

FIG. 2 is a side view of the fishing pliers of FIG. 1;

FIG. 3 is another side view of the fishing pliers of FIG. 1;

FIG. 4 is a front view of the fishing pliers of FIG. 1;

FIG. 5 is a rear view of the fishing pliers of FIG. 1;

FIG. 6 is a top view of the fishing pliers of FIG. 1; and,

FIG. 7 is a bottom view of fishing pliers of FIG. 1.

The broken lines shown in FIGS. 1-7 represent portions of the fishing pliers that form no part of the claimed design. The dash dot line represents a border that does not form part of the claimed design.
